NECKTIE WITH LOCATING MEANS
Maurice M. Light, 151 N. Kenilworth Ave.,
Oak Park, Ill. 60301
Filed Dec. 14, 1965, Ser. No. 513,790
9 Claims. (Cl. 2—146)

This invention relates to an improvement in neckties, especially of the four-in-hand type, one of the purposes being to facilitate the location of the knot at the proper place so as to align the necktie as desired. In some instances it is desired to align the wide front side of the necktie with the narrow front side of the necktie. However, it may also be desired to align the wide front side with the belt, top of pants, etc., and the knot location device of this invention can be employed for any of these preferences.

There are numerous prior art necktie marking devices to aid in locating the proper place to tie a knot. Most of these have defects in that they are not adjustable, detract from the appearance of the necktie, rely on the sense of sight alone when tying the knot, are difficult to clean without damage to the necktie, and/or injure or mar the material of the necktie when the marker is attached thereto. My invention alleviates all of these shortcomings and is a substantial improvement over all these prior art markers.

It is an object of this invention to provide a marker for locating the position of a knot on a necktie which can be either accentuated or decentuated (defined herein to mean de-emphasize) at will.

It is another object of this invention to employ a necktie marker which is soft and pliable thereby permitting the mark to remain when the necktie is twisted, moved, cleaned, washed, etc.

It is another object of this invention to employ a necktie marker which will permit the wearer to tie a knot in a necktie in the proper location with the aid of his visual and/or touch senses.

It is still another object of this invention to indicate what type of a knot the necktie marker is set for.

It is a further object of this invention to employ a stitching mark to locate the position in which to tie a knot in a necktie, said stitching mark being able to be used in all types of necktie materials, not detracting from the appearance of the necktie and if desired being part of the necktie thread stitches.

It is another object of this invention to allow all wearers of neckties, whether they be short or tall and whether they have a small or large neck size, to tie any style of knot in a location preferable to the individual wearer.

It is still another object for a wearer to tie a knot in his necktie in the proper location on the first attempt by relying on the accentuated necktie marker of this invention.

These and other objects will become more apparent in the light of the following detailed description.

FIGURE 1 of the accompanying drawing shows a preferable embodiment of a necktie with the marking stitches.

FIGURE 2 shows a side view of FIGURE 1.

FIGURE 3 shows an enlarged portion of zone 1 in FIGURE 1.

FIGURE 4 shows an alternate preferable embodiment employing vertical marking stitches.

FIGURE 5 shows a side view of FIGURE 4.

FIGURE 6 shows another preferable embodiment having the marking stitches attached to a patch material and the patch material attached to a necktie.

FIGURE 7 shows a side view of FIGURE 6.

2

Referring to FIGURE 1, a necktie 4 is shown in full length containing a wide end 15, a narrow end 16 and a neckband 20 therebetween. Since necktie 4 is viewed from the back side, only a small portion of the front side 5 of the necktie is shown while back side 6 runs practically the entire length. The necktie is divided into three zones of marking stitches, each serving a different purpose. The most important, zone 1, comprises the marking stitches to accurately locate the place in the wide end at which the first fold is made to tie the knot in the proper position in the necktie. Zone 1 is composed of a series of decentuated marking stitches 9 and one accentuated marking stitch 10. Zone 1 is associated with wide end 15 of necktie 4. In most cases, a man ties his necktie by winding the wide end around the narrow end of the necktie. The position of the first fold in the wide end when tying the knot generally determines the final position of the knot with respect to each end and accordingly the marking stitches in zone 1 must be accurately calibrated in order to achieve precise location of the knot. The accentuated marking stitch locates the position at which the first fold is made in the wide end. The marking stitches should be spaced at least about $\frac{1}{32}$ of an inch apart and preferably from about $\frac{1}{4}$ to about $\frac{1}{2}$ of an inch in order to attain sufficiently accurate calibration. The length of zone 1 should extend for at least about 2 inches and preferably at least about $\frac{1}{3}$ of the entire length of the necktie. Zone 1 is located between about $\frac{1}{6}$ to about $\frac{2}{3}$ of the length of the necktie from the wide end and preferably from about $\frac{1}{5}$ to about $\frac{1}{2}$ of the length. Preferably the stitching marks are made out of a continuous filament which is woven over and under the back side of the necktie, said filament having sufficient slack length to allow one of the stitching marks to be pulled away from the back side to form an accentuated stitching mark. Then when it is desired to accentuate a different stitch mark, said different stitch mark is pulled away from back side 6 and thereby automatically decentuating the old mark. In actual practice the wearer will determine the correct position for mark 10 by trial and error until the resulting knot is in the desired position and the wide end of the necktie is aligned as desired. Thereafter the wearer merely need make the first fold in the wide end at mark 10 to obtain the desired knot in the proper location on the first attempt.

Zone 2 is associated with the narrow end 16 of necktie 4. It is also composed of a series of decentuated stitching marks 7 and one accentuated mark 8. The accentuated mark 8 functions in a similar manner to the narrow end 16 as mark 10 functioned for wide end 15. Thus to tie the necktie the wearer would line up mark 8 and 10 together and tie his knot. Generally it is not necessary to have a mark on the narrow end since the wide end is wound around the narrow end and the point of the first fold in the wide end determines the knot location. However, sometimes the first fold line can slip or shift a little depending on how a wearer ties his knot which can mis-position the knot. But, if the wearer trains himself to wind the knot around the same point on the narrow end, the slippage can be compensated for since it will then be constant each time the knot is tied and thus the position of the knot can be carefully controlled. It is not necessary to have as precise a calibration of marking stitches in zone 2 as was preferable in zone 1. Generally spacing of markings as far apart as 1 inch is satisfactory although closer spacings of from about $\frac{1}{4}$ to $\frac{1}{2}$ inch are better.

Zone 3 is employed to remind the wearer as to what kind of a knot marks 8 and 10 are set for. Thus zone 3 is composed of three sets of decentuated marks 11. The first set having one mark is for the simple four-in-hand knot.

The second set having two marks is for knots that are variations of the four-in-hand knot. The third set having three marks, one of which is accentuated mark 12, is for the "Windsor" knot. The sets of zone 3 can likewise be formed of single marks. Tabs having symbols carried thereon may also be placed opposite each set to remind the wearer which type of knot the marks are calibrated for. For example, a cloth tab with the letter F is attached alongside the first set indicating four-in-hand knot, a second tab with the letter T is attached alongside the second set indicating a two-loop knot and a third tab with the letter W is attached alongside the third set indicating a "Windsor" knot. Although zone 3 is shown in the wide end portion of the necktie, it can also be placed in any other convenient location such as the neckband or the narrow end.

It is manifestly apparent that neckties will produce knots of varying thickness depending on materials, lining, etc. Thus a wearer will have a difficult time in tying knots in the proper location for the wide variety of neckties that are present in a typical wardrobe. This invention will alleviate this problem and save the wearer time and avoid aggravation by allowing the knot to be tied in the proper location on the first try (after presetting the accentuated marks). It is possible to have a continuous filament connecting all three zones with sufficient pre-set slack length in each zone to provide one accentuated stitching mark. A continuous series of stitching marks may also be employed for a dual function; marking as described hereinbefore, and also to hold the seam of the back side together. When using a continuous series of stitching marks the zones may be distinguished by different color stitchings, different texture stitchings, etc.

FIGURE 2 is a side view of FIGURE 1 and shows a continuous stitching filament 14 employed throughout all three zones. The filament 14 runs along the length of necktie 4 forming zone 2, comprising of decentuated stitching marks 7 and accentuated stitching mark 8; zone 1 comprising decentuated stitching marks 9 and accentuated stitching mark 10; and zone 3 comprising decentuated marks 11 and accentuated mark 12. In between these zones, filament 14 runs in the volume formed between front side 5 and back side 6. Small knot 17 is located at the narrow end of the necktie and small knot 18 is located at the wide end of the necktie, said knots being employed to anchor the filament into the back side of the necktie.

FIGURE 3 is an enlargement of zone 1 shown in FIGURE 1 with the underneath portion of filament 14 shown in dotted lines. Back side 6 of a necktie is shown having a series of decentuated stitching marks 9 and one accentuated mark 10.

FIGURE 4 shows an alternate manner of forming the stitching marks, namely, by forming a series of vertical marks (parallel to the line connecting the narrow end to the wide end) instead of the near horizontal marks shown in FIGURES 1 and 3. In actuality the marks may be in any position from vertical to horizontal although if they are in a true horizontal position the filament may tend to bind when adjusting the accentuated mark. Again in this figure back side 6 is shown having a series of decentuated marks 9 and one accentuated mark 10 along with the visible and underneath (shown in dotted) portions of filament 14.

FIGURE 5 is a side view of FIGURE 4 showing the front side 5 and the back side 6 of the necktie in which filament 14 is woven through the back side forming a series of decentuated marks 9 and one accentuated mark 10. Also shown is small knot 19 anchoring one end of filament 14 into back side 6.

Another preferable embodiment of the present invention is shown in FIGURES 6 and 7 and relates to the placing of a series of marking stitches on a patch material and attaching the patch material to the back side of the necktie. Thus the zones of the stitching marks are woven

into the patch material and thereafter the patch cloth is attached to the back side of the necktie by means such as tape, pins, etc. or preferably the patch cloth is sewn directly onto the necktie. The patch material is preferably thin relative to the thickness of the necktie in order to avoid adding bulkiness to the necktie. In FIGURE 6 patch material 21 is shown sewn onto the back side 6' of necktie 4'. The patch material carries a filament 14' woven therein forming a series of decentuated stitching marks 9' and one accentuated stitching mark 10'. FIGURE 7 is a side view of FIGURE 6 showing the front side 5' and the back side 6' of necktie 4' and patch material 21 carrying filament 14', said filament forming a series of decentuated stitching marks 9' and one accentuated mark 10'.

The stitching material is a filament and may be made of any convenient material such as ordinary thread, elastic, plastic, stretch thread, etc. Especially preferable is that type of thread which tends to ball up when tension is removed. Thus when using this type of stitching material the accentuated mark would ball up forming a bulge which can easily be seen and felt when tying the necktie. This stitching material should be soft and pliable so that the tie can be twisted and moved without moving the accentuated mark. The material should be of a type which can be cleaned either by dry cleaning or by wet cleaning without loss of strength, stretching, fading, etc.

The stitching mark should be of sufficient cross length so as to permit ready access of a fingernail thereto. The length of the mark should be no more than about $\frac{1}{2}$ of an inch and is preferable about $\frac{1}{4}$ of an inch. The loop formed by the accentuated mark should be appreciable to allow its presence to be felt either by sight or touch.

It is to be understood that in its broadest sense this invention may be used on all types of neckties not only the four-in-hand type but of other types including bow ties.

I claim as my invention:

1. A necktie which comprises:

a neckband;

a wide end extending from the neckband having a front side and a back side;

a narrow end extending from the neckband having a front side and a back side;

a continuous filament attached to the back side of the necktie forming a visible series of decentuated stitching marks, said filament having sufficient slack length to allow one of the stitching marks to be pulled away from the back side to form a first accentuated stitching mark; and

means to secure the ends of the filament to the necktie.

2. The necktie of claim 1 further characterized in that the stitching marks are directly sewn into the back side of the necktie, are spaced apart at least $\frac{1}{32}$ of an inch and extend for at least about 2 inches in length.

3. The necktie of claim 1 further characterized in that a patch material is directly attached to the back side of the necktie and the filament is directly sewn into the patch material to form said series of stitching marks thereon.

4. The necktie of claim 2 further characterized in that the narrow end carries a second visible series of decentuated stitching marks formed by passing a continuous filament over and under the back side with sufficient slack length to allow one of said marks to be accentuated.

5. The necktie of claim 2 further characterized in that another series of visible stitching marks are carried by the necktie to indicate the type of knot the first accentuated stitching mark is set for, one of the other series of marks being accentuated.

6. The necktie of claim 4 further characterized in that a third series of visible stitching marks are carried by the necktie to indicate the type of knot the first accen-

tuated stitching mark is set for, one of the third series of marks being accentuated.

7. The necktie of claim 6 further characterized in that the filament is made of a ball up type of thread.

8. The necktie of claim 6 further characterized in that the filament forms the stitching on the back side to hold the seam of said back side together.

9. The necktie of claim 6 further characterized in that the stitching marks are positioned from near horizontal

to substantially vertical with respect to the vertical line connecting the wide end to the narrow end.
